Primary Examiner — Nicole C Shiflet*Assistant Examiner* — Danielle Nichole Bowly(74) *Attorney, Agent, or Firm* — RatnerPrestia(57) **CLAIM**

The ornamental design for an imprinter for scanner, as shown and described.

DESCRIPTION

FIG. 1 is a perspective view of an imprinter for scanner showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines in the drawings are for the purpose of illustrating unclaimed portions of the imprinter for scanner and form no part of the claimed design.

1 Claim, 5 Drawing Sheets(56)
